UNITED STATES PATENT OFFICE.

LOUIS H. PERLMAN, OF NEW YORK, N. Y.

WHEEL.

1,287,418.

Specification of Letters Patent. Patented Dec. 10, 1918.

Application filed August 16, 1917. Serial No. 186,532.

To all whom it may concern:

Be it known that I, LOUIS H. PERLMAN, a citizen of the United States, residing at New York, in the county of New York and State of New York, have invented certain new and useful Improvements in Wheels; and I do hereby declare the following to be a full, clear, and exact description of the invention, such as will enable others, skilled in the art to which it appertains to make and use the same.

This invention relates to improvements in demountable rims for automobile wheels, and more particularly to the type known as transplit or crosscut, that is, the type wherein an otherwise continuous tire-carrying ring is transversely cut for enabling the ring to be relatively reduced in effective diameter for permitting the application and removal of tires having inextensible beads.

The object in view is the provision of simple and effective means whereby the adjoining ends of a transplit rim may be readily secured or detached.

With this and more detail objects in view, as will in part hereinafter become apparent and in part be stated, the invention comprises certain novel constructions, combinations and arrangements of parts as subsequently specified and claimed.

In the accompanying drawings,—

Figure 1 is a fragmentary plan view looking at the outer face of the rim.

Fig. 2 is a similar view looking at the inner face of the rim.

Fig. 3 is a sectional view taken on the plane indicated by line 3—3 of Fig. 2.

Fig. 4 is a sectional view taken on the plane indicated by line 4—4 of Fig. 2.

Fig. 5 is a perspective view of the latch plate detached.

Fig. 6 is a view similar to Fig. 1 of a slightly modified embodiment of the invention.

Fig. 7 is a perspective view of the latch plate employed in the structure seen in Fig. 6.

Fig. 8 is a perspective view of the retaining button detached.

Referring to the drawing by numerals, 1 indicates a demountable rim of the usual cross-cut type, the rim being cross-cut at the point 2, leaving rim terminals 3 and 4.

A latch plate is connected to terminal 3

to engage terminal 4. The said latch plate 5 consists of a tongue 5, which, as illustrated, comprises a strip of metal, but may be formed otherwise when preferred. The tongue 5 is constructed with outstanding shoulders 6, 6, at one end and an enlarged portion 7 extending substantially at right angles with the main part of the tongue at the other.

The latch plate 5 is electrically welded, riveted or otherwise fixed to the outer surface of rim 1, at the terminal 3, and extends from terminal 3 to and into engagement with terminal 4 as will hereinafter be clearly explained. The terminals of rim 1 are formed offset, as at 8 and 9, by stamping or any other appropriate means, the said offset being sufficiently depressed to allow the tongue 5 to have its outer surface lie flush with the outer surface of the base of rim 1. The free end portion 7 of the tongue 5 when applied to the rim is positioned in the aperture 10 and abuts the offset portion of the rim for latching or retaining the ends of rim 1 in their relatively closed relation. The offset 8 terminates at one of its ends along the cut line 2 and at the other end the offset is severed from the material of the base of rim 1, along the line 11 corresponding in contour to the end portion of tongue 5 and having the shouldered projections 6', 6' corresponding to the shoulders 6 and on which the projections forming shoulders 6 lie flat.

In order to relieve the stress placed on the securing means attaching the latch plate 5 to the offset portion 8 of the rim terminal 3, the outstanding shoulders 6, 6, are so positioned against the opposite edges of the offset 8 as to deliver stresses directly to the rim end 3 and thus proportionally relieve the weld or other means of connection of tongue 5 with offset portion 8.

As clearly seen in Fig. 3, the projection 7 is not exactly at right angles to the tongue 5, but is slightly inclined and the edge of offset 9 along the opening 10 is similarly inclined so as to form an effective locking connection between the parts.

In Figs. 6 and 7, I have illustrated a slightly modified embodiment in which the tongue 5 corresponds with tongue 5 above described, and is provided with the shoulder portions 6'' engaging the terminal 3' of rim 1' which rim is cross-cut at 2'. The termi-

- nal 4^a of said rim is recessed at 10' for receiving the projections 7' of tongue 5^a. The recess 10' differs from recess 10 only in that the ends of the recess are extended laterally 5 beyond the planes of the edges of tongue 5^a and formed with abrupt shoulders corresponding in contour to the shoulders engaged by the shoulder portion 6''. Extending laterally from the tongue 5^a at the ends of the 10 projections 7' are extensions or shoulder portions 7^a fitting the terminals of the aperture 10'. This modified embodiment thus conforms in all details to the embodiment above described except that the free end of the 15 latch is provided with lateral projections adapted to serve as additional stress distributing members for delivering stresses to the rim terminal 4^a in addition to those delivered by the projection 7^a.
- 20 In operation, the rim 1 is collapsed or distorted axially as preferred for the removal and application of a tire as is well understood in the manipulation of cross-cut demountable rims.
- 25 While the structures above described are complete as described and are adapted for effective operation, it has been found desirable under certain conditions to provide means for preventing accidental withdrawal 30 of the projection 7 from the aperture 10, and to this end I employ a plate 15 mounted to serve as a turn-button. The plate 15 is pivoted at 16 to the rim 1 in position for having one of its ends swing to and from a location in engagement with a groove 17 formed 35 in the projection 7. To prevent undesirable pivotal movement of the plate 15, the plate is formed at that face which contacts with the inner face of rim 1 with a recess 18 engaged by a projection 19 formed on the rim 1. The said projection and recess may be formed by the use of a punch and when the two are interlocked, as indicated in Fig. 3, the plate or button will be held against dislocation. When it is desired to disengage 40 the button from the projection 7 a tool is placed in a notch 20 formed in the edge of plate 15 and the plate is caused to move pivotally by the pressure of such tool. The tool 45 may be driven by hammer blows if found necessary.
- What is claimed is:—
1. In a rim structure, the combination with a cross-cut demountable rim having depressed portions at its ends, of a latch plate let into one depressed portion and having a lateral extension disposed to engage the edge of said depressed portion, the said latch plate being formed with means at its opposite end portion for engaging the depressed portion at the other end of the rim.
  2. In a rim structure, the combination with a cross-cut demountable rim, of a latch plate let into one end portion of the rim and having lateral extensions engaging corre-
- sponding portions of the rim at right angles to the plate, the said latch extending beyond the engaged end portion and having means for engaging the opposing end portion of the rim. 70
3. A demountable rim comprising a cross-cut rim body having circumferentially extending depressions in its end portions and an aperture at the terminal of one depression, the corresponding terminal of the other depression being formed with lateral recesses, and a latch plate having lateral projections provided with shoulders occupying said lateral recesses and engaging the walls thereof, the latch being formed with a projection adapted to extend through the aperture of the apertured end portion. 75
4. A demountable rim comprising a cross-cut rim body having circumferentially extending depressions in its end portions and an aperture at the terminal of one depression, the corresponding terminal of the other depression being formed with lateral recesses, and a latch plate having lateral projections provided with shoulders occupying 80 said lateral recesses and engaging the walls thereof, the latch being formed with a projection adapted to extend through the aperture of the apertured end portion, the said depressions being of a depth and location 85 causing the latch while lying at the outer face of the rim to lie flush with such outer face. 90
5. A demountable rim comprising a cross-cut rim body having circumferentially extending depressions at its terminals and an aperture at one end of one of the depressions, said aperture having lateral extensions beyond the longitudinal planes of the depressions and the depression at the other end 100 portion having corresponding lateral extensions and a latch fixed to the last-mentioned end portion and having extensions conforming to the contour of the extensions of the depression and of the aperture. 105
6. A demountable rim comprising a cross-cut rim body having circumferentially extending depressions at its terminals, and an aperture at one end of one of the depressions, said aperture having lateral extensions 110 beyond the longitudinal planes of the depressions, and the depression at the other end portion having corresponding lateral extensions, and a latch fixed to the last mentioned end portion and having extensions conforming to the contour of the extensions of the depression and of the aperture. 115
7. In a rim structure, the combination of a cross-cut demountable rim and a latch plate disposed circumferentially of the rim and extending across the cut thereof, said plate having lateral extensions at one end and a latch projection at the other, and the 120
- 65
- 130

rim being depressed in its base for accommodating the said latch plate with its projections.

8. The combination with a cross-cut 5 mountable rim formed with an aperture adjacent one of its ends, of a latch plate fixed to the other end of the rim and disposed to lap the first-mentioned end, the latch plate being formed with a projection adapted to 10 extend through the aperture, the said projection being formed with a groove, and a turn-button pivoted to the rim in position

for swinging into and out of the groove, the turn-button being formed with a recess and the rim with a corresponding projection 15 adapted to enter the recess for retaining the turn-button against pivotal movement.

In testimony whereof I affix my signature in presence of two witnesses.

LOUIS H. PERLMAN.
